Filed Oct. 22, 1964, Ser. No. 82,281

Term of patent 14 years

(Cl. D90—20)

Fig. 1

*Fig. 2**Fig. 4*FIG. 1 is a perspective view of a tire embodying our new design, it being understood that the full line portion is repeated throughout the circumference of the tire, shown by means of broken lines;

FIG. 2 is an enlarged fragmentary plan view of the tread portion of the tire shown in FIG. 1;

FIG. 3 is a sectional view taken substantially on the plane indicated by line III—III of FIG. 2, but on a reduced scale; and

FIG. 4 is an enlarged fragmentary side elevational view of the outer sidewall portion of the tire shown in FIG. 1, but on the same scale as FIG. 3.

The dominant features of our design reside in the tread and outer sidewall portions of the tire illustrated in the drawings.

We claim:

The ornamental design for a tire, substantially as shown and described.
